(57) **CLAIM**

The ornamental design for a shirt with back pocket, substantially as shown and described.

DESCRIPTION

FIG. 1 is a front perspective view of a shirt with back pocket showing the claimed design.

FIG. 2 is a rear perspective view of the shirt with back pocket of FIG. 1, showing the pocket flaps in a closed position.

FIG. 3 is a front view of the shirt with back pocket of FIG. 1.

FIG. 4 is a rear view of the shirt with back pocket of FIG. 1, showing the pocket flaps in a closed position.

FIG. 5 is a left side view of the shirt with back pocket of FIG. 1, showing the pocket flaps in a closed position.

FIG. 6 is a right side view of the shirt with back pocket of FIG. 1, showing the pocket flaps in a closed position.

FIG. 7 is a top view of the shirt with back pocket of FIG. 1, showing the pocket flaps in a closed position.

FIG. 8 is a bottom view of the shirt with back pocket of FIG. 1, showing the pocket flaps in a closed position.

FIG. 9 is a partial enlarged view of the pocket shown in FIG. 4; and,

FIG. 10 is a partial enlarged view of the pocket shown in FIG. 4 in an alternative configuration, showing the pocket flaps in an open position and access to the interior through-hole, which is shown in FIG. 3.

The broken lines in FIGS. 1-10 showing the shirt are for illustrating the environment of the claimed design. The broken lines within the rectangle of FIG. 10 are for illustrating environment of the pocket. All broken lines shown in FIGS. 1-10 form no part of the claimed design.

1 Claim, 10 Drawing Sheets
